UNITED STATES PATENT OFFICE

CARL M. PETERSEN, OF TRENTON, NEW JERSEY, ASSIGNOR TO CIRCLE F MFG. CO., OF TRENTON, NEW JERSEY, A CORPORATION OF NEW JERSEY

PULL SWITCH CANDLEABRUM SOCKET

Application filed April 20, 1928. Serial No. 271,513.

This invention relates to a novel structure for candelabrum sockets of the pull switch type and has for its primary object a facile assembly of parts which simplifies and cheapens the manufacture of the article and involves novel structural features of practical importance in the art. The improvements contemplated are especially designed for use in a screwless-type structure 5 wherein the entire assembly may be made without the use of any screws or separate fastening devices, and all of the pull switch mechanism may also be mounted without the use of screws as fastening means and carried 10 as an entirety by one of the sections of the insulating socket body so that in the act of assembling the parts the movement of the insulating body section causes the body and screw shell to come into direct interlocking 15 engagement and the entire switch becomes housed within the socket body in its operative position.

Another object of the invention is to provide for a convenient and selective position 25 of the pull chain so that it may be guided in any of several positions according to the situation met in the house or building where the socket is installed.

With these and other objects in view which 30 will more readily appear to those familiar with the art as the invention is better understood in detail, the same consists in the novel construction, combination and arrangement of parts shown in the accompanying drawings and set forth in the following description and claims.

The essential features of the invention necessarily are susceptible of modification without departing from the spirit or scope 40 of the invention but a preferred and practical embodiment thereof are shown in the accompanying drawings, wherein:

Figure 1 is a side elevation of a pull switch candelabrum socket constructed in accordance with the present invention.

Figure 2 is another elevation from a different side of the socket from that shown in Fig. 1.

Figure 3 is a sectional view of the socket 50 on the line 3-3 of Fig. 1.

Figure 4 is a sectional view of the socket on the line 4-4 of Fig. 2.

Figure 5 is an inside face view of one of the sections of the socket body with the switch assembly removed from said block and exposing the fixed spring contacts.

Figure 6 is an end view of the socket body with the screw shell contact removed.

Figure 7 is an end view of the screw shell contact exposing the locking hole therein.

Figure 8 is a detail view illustrating the relative arrangement of the parts to provide the locking together of the socket body and the screw shell in the act of assembling these parts.

Figure 9 is a sectional elevation of a complete candelabrum fixture showing one of the preferred applications of the invention.

The novel candelabrum socket, representing the present invention includes in its general organization a socket body B of porcelain or other insulated material, a screw shell contact C, a retainer member R, and a switch assembly S, the latter being entirely housed within the switch housing chamber 1, which is entirely closed in when the two sections 2-2 of the socket body B are brought into contacting matching relation.

The socket body B is preferably of an elongated form to adapt it for a candelabrum socket and except for the recessing to provide for the housing of the switch mechanism S and the seating a few detail elements, is of a solid formation so as to give stability and strength to the entire structure, and as indicated, the same is of a separable two-part construction, the separate sections 2-2 thereof having inner flat faces 3-3 which solidly abut when the said sections are assembled and in matching relation. As more

clearly shown in Fig 3 of the drawings the same end of the socket body B each section thereof is provided with an under-cut catch hook 4-4 in registering relation with the similar catch hook of the other section in order to provide a divided two-part rectangular lock lug L. This lock lug is adapted to project through and interlock with the rectangular locking hole 5 cut into the base or bottom

6 of the screw shell contact C.

The described construction provides for the socket body B and screw shell contact C to become securely and directly locked together without the use of screws or separate fastenings of any kind. This locking engagement is effected by holding the body sections in a divided spread-apart position shown in the detail view of Fig. 8 of the drawings, inserting the catch hooks 4-4 as thus brought to closer relation through the locking hole 5 of the screw shell contact, and then moving the body sections into the solid abutting contact as shown in Fig. 3. This results in bringing the under-cut portions of the catch hooks 4-4 over opposite edges of the hole 5, thereby securely locking the parts together so that the screw shell contact cannot be removed from the socket body without reversing the operation just described. To retain the two sections of the base block in this final relation a suitable retaining means is employed, such for instance as the retainer member R consisting of a one-piece yoke or bracket having the opposite side arms 7-7 and a connecting end member 8, the latter member having the attaching opening 9 facilitating the attachment of the socket to the house fixture. The said side arms 7-7 of the retainer or retaining member R have their ends seated in the recessed seats 10 in the opposite body sections 2-2 at one end thereof, and such ends of said side arms are connected by a through screw 11 passing through the aligned screw openings 12 in the said body sections.

A characteristic improvement provided by the present invention is that of mounting the entire switch mechanism on one of the body sections 2 so that such switch mechanism is supported and held in operative relation by such section and not disturbed in such relation by the movement of the two body sections either in the locking or unlocking operation with the screw shell contact. This switch mechanism preferably includes a ratchet type rotor r mounted on a switch axle 13, whose ends extend into the axle openings 14 and 15 respectively in the opposite body sections 2-2, the smaller hole 15 being in the body section which carries the whole switch assembly and at the outer side of which hole the said body section is countersunk as at 16 to accommodate the flattened holding head 17 of the said axle 13. This flattened holding head 17 is adapted to be seated, when turned in a position at right angles to that shown in Fig. 1 of the drawings, in the locking seats 18-18 provided in the bottom of the countersink 16; and when turned to the position shown in Fig. 1 in line with the longitudinal axis of the socket will permit a ready attachment of the whole switch assembly.

The rotor r is of the ratchet type including the usual tensioning spring 19 on the axle at

one side thereof and carrying at its opposite side the double switch arm 19 adapted to have a ratchet engagement with the oppositely disposed fixed switch-contacts 20 and 21, both of which fixed contacts are preferably fastened to the same body block 2 by eyelet or equivalent fixed fastening elements 22 thereby dispensing with the use of screws at these points. The fixed switch contact 20 is connected directly by its eyelet fastening 22 with the outside binding terminal 23 seated in a terminal recess 24 in the outside of one of the body sections 2 and carrying the usual binding screw 25. The other fixed switch contact 21 which is fastened to the said body section 2 is preferably held by its eyelet fastening 22 to the inside arm 26 of the center plug fastening 27 consisting of a single bent plate or strip held within the holding groove 28 formed in the upper end of one of the body sections 2 and having one end enlarged and exposed within the screw shell to form the actual center plug contact. The electrical circuit is completed by the second binding terminal 29 soldered or otherwise rigidly fastened at one end as at 30 to the screw shell contact and carrying at its other end the binding terminal 31 set within the terminal recess 32 at one side of the body.

The switch mechanism includes as the operating element thereof the usual pull chain 33 connecting at one end with the rotor r of the housed switch assembly and its free running portion being adapted for guidance at either side of the rounded division lug 34 of a divide formation—a part thereof on each of the body sections 2-2 so that when the said sections are matched a chain guiding opening 35 is formed at the inner side of the said lug and a chain guiding groove 36 is formed at the outer side of the said lug. By reason of this construction the pull chain 33 may be directed in either of several directions as indicated by the full and dotted lines in Fig. 4 of the drawings according to the position and requirements for the socket in any particular location.

In one of the preferred applications of the invention, shown in Fig. 9 of the drawings, the practical utility of the retainer and attachment member R is emphasized. This member is preferably, as shown, in the form of a bracket or yoke and it provides a combined means for holding the two porcelain parts of the socket together, and also as an attachment or mounting means for mounting and supporting the device itself. Referring to the illustration of Fig. 9 showing this dual function of the member R it will be seen from that figure that the entire pull switch socket is intended to be entirely housed within the candle-shell 37 suitably carried by the fixture or wall plate 38 and in this particular application may be provided with a bottom rounded end portion 39 upon which

the socket itself is seated and which end portion is provided with an outlet opening or hole into which may project the bracket or yoke member R. The application here shown 5 also illustrates the device for use with the chain 33 arranged for a direct pull thereon in line with the longitudinal axis of the device. To provide for this a holding element 40 in the form of a hollow headed screw may 10 be employed, the said screw engaging the threaded opening 9 in the cross-piece of the bracket or yoke R and passing through and engaging a perforated and shouldered clamping cap 41, the said cap 41 and the 15 candle-shell 37 being of porcelain or other insulating material. With this construction the chain 33 operates directly through the hollow screw 40 in line with the longitudinal axial center of the device. The chain is provided at its lower end with the usual pull 20 knob 42 of a suitable form.

From the foregoing it is thought that the construction, action and advantages of the invention as herein described, will be readily 25 understood without further description and it will also be understood that changes in the form within the scope of the invention will be resorted to without departing from the invention.

30 I claim:—

1. A pull switch candelabrum socket, including a separable two-part body, a screw shell having a direct interlocking engagement with the two sections of the body at 35 one end, a combined fixture attaching bracket and body section holding means engaged with the sections of the body at the opposite end, and a switch carried by the body.

2. In a pull switch candelabrum socket, a 40 separable two-part socket body, a screw shell contact directly interlocking with the body by the act of assembling the body therewith, a combined attaching bracket and retaining device holding the body sections together, 45 and a pull switch mechanism carried by one of the body sections.

3. A pull switch candelabrum socket, including in its organization a separable two-part socket body made of insulating material, said body being recessed and provided 50 at one end with a division lug forming a chain guiding opening and chain guiding groove respectively at opposite sides thereof and communicating with a recess of the body, and a pull switch mechanism housed within the body and including a rotor and a pull chain adapted to be directed through either the said chain guiding opening or through the said chain guiding groove.

60 4. In a pull switch candelabrum socket, a separable two-part body socket, a screw shell contact directly interlocked with the body by the act of assembling the body therewith, a combined attaching bracket and re- 65 taining device holding the body sections to-

gether at one end and a pull switch mechanism carried solely by one of the body sections.

In testimony whereof I hereunto affix my signature.

CARL M. PETERSEN.
